1,4-BIS(D-GLUCOSYL)PIPERAZINE AND PROCESS OF PREPARATION

Tellis A. Martin, Evansville, Ind., assignor to Mead, Johnson & Company, Evansville, Ind., a corporation of Indiana

No Drawing. Application October 18, 1956
Serial No. 616,583

2 Claims. (Cl. 260—211.5)

This invention relates to a reaction product of glucose and piperazine and more specifically to 1,4-bis-(D-glucosyl)piperazine having the following structural formula:

It has been known that piperazine derivatives in general and particularly piperazine hexahydrate and several salts thereof are useful as anthelmintics and more particularly as oxyuricidal agents. These compounds, while having utility in this application, are subject to a drawback of having rather toxic side effects on some patients at therapeutic dosages. These toxic side effects of the piperazine compounds described above are noted in the British Medical Journal, page 1272, Dec. 5, 1953, and a number of similar publications which have appeared more recently.

Accordingly the compound of the present invention is useful as an anthelmintic and more particularly as an oxyuricidal agent which has greatly reduced toxic side effects and is in general considerably less toxic than the prior art piperazine compounds which have been used for this purpose.

Generally this compound may be administered orally in the form of wafers, capsules, tablets, powders, liquid suspensions, and the like. The dosage for an adult will usually be from about 2500 to 5000 milligrams per day, administered from once to several times daily to achieve the desired therapeutic effect.

The following table will illustrate the relative toxicity of the compound of the present invention, as compared to the prior art piperazine hexahydrate and piperazine salts.

TABLE I

Toxicity of piperazine-containing compounds

Composition:	LD ₅₀ (orally) (mgs./kg.) ^a
Piperazine hexahydrate	2880
Piperazine adipate (tech.)	^b 3035
Piperazine citrate	^c 3400
Mechanical mixture of one mole of piperazine and two moles of glucose	2646
1,4-bis(D-glucosyl)piperazine	6510

^a All values are based upon the piperazine content, and the LD₅₀ values were determined in white mice, p.o.

^b J. Pharm. and Pharmacology VI, 711 (October 1954).

^c J. Am. Med. Assoc. 161, 515 (1956).

As may be seen from this table, the LD₅₀ values are stated in terms of the piperazine content and it should be further noted that there is also included in that table an LD₅₀ value for a mechanical mixture of one mole of

2

piperazine and two moles of glucose which was included to show that the lack of toxic properties of the compound of the present invention is an inherent characteristic of the compound itself and not a result of dilution of the piperazine content by the substitution of large substituents on the parent piperazine structure. With reference to the prior art piperazine hexahydrate and piperazine adipate which are used as oxyuricidal agents, the LD₅₀ values obtained are about 3000 milligrams per kilogram which is less than one-half of the LD₅₀ value for 1,4-bis-(D-glucosyl)piperazine which has an LD₅₀ of 6510 milligrams per kilogram.

The 1,4-bis(D-glucosyl)piperazine of this invention may be readily synthesized by the direct reaction of glucose and piperazine or piperazine hexahydrate. Usually the best and quickest results are obtained when glucose and piperazine are heated together at 60° to 85° C. for 4 to 10 hours. Increase in temperature and concentrations of the reactants will generally result in a more rapid reaction rate and the reaction is preferably carried out in the presence of an aqueous or nonaqueous solvent.

The product of the present invention is a soft powder having a melting point range of between about 168° and 191° C. with decomposition. This wide range in melting point is believed to be due to existence of a mixture of different proportions of alpha and beta glucosyl groups in the final product which may depend upon the particular method of preparation. The product of the present invention shows an infrared absorption band at 843 cm.⁻¹ which is in the range 835 to 855 cm.⁻¹ characteristic of α-D-glucosylamines. The product of the present invention is also characterized in that it has rather low solubility in the usual organic solvents, water and dilute alkaline medium. The product is more readily soluble in strong mineral acids such as hydrochloric acid.

The following are examples of methods for preparing the product of this invention:

EXAMPLE 1

A mixture of 29.3 g. (0.163 mole) of D-glucose (anhydrous), 14 g. (0.163 mole) of anhydrous piperazine and 850 milliliters of absolute methanol was heated under reflux for four hours. On cooling, the slightly yellow solid was collected on a filter, washed with methanol and dried. Yield: 20 g. of M.P. 190° C. (d). Two additional fractions of solid product were obtained by concentrating the above filtrate: 4 g. of M.P. 184–192° C. (d) and 2 g. of M.P. 189–191° C. (d). Total yield: 26 g. (78%, based on glucose). Fraction (1) was slurried with methanol to give product with M.P. 187–189° C. (d) with darkening at about 160° C. However, with fast heating this darkening does not occur until somewhat higher temperatures and as a result higher decomposition points are obtained.

Analysis.—Calc. for C₁₆H₃₀N₂O₁₀: C, 46.82; H, 7.37; N, 6.83. Found: N, 6.50, 6.50.

Less expensive starting materials such as piperazine hexahydrate and glucose monohydrate may be employed in this reaction. Also small amounts of catalyst, such as hydrochloric acid or ammonium chloride, may be employed. Other alcohols (ethanol, isopropanol, propylene glycol, etc.) may be used as reaction solvent.

EXAMPLE 2

A mechanically stirred mixture of 216 g. (1.2 moles) of D-glucose, 116.4 g. (0.6 mole) of piperazine hexahydrate and 360 ml. of propylene glycol was warmed to about 75° C. by external heating with an oil bath. Complete solution resulted at this point and a filtration step may be included here to remove any trace of solid impurity. Then on continued heating at 75–80° C. for 10–20 minutes, a cloudiness appeared and the solid product began to precipitate. Then by the use of a Dean-

Starke water separator, the theoretical quantity of water was collected as a benzene-water azeotrope. The reaction temperature of 80-84° C. was maintained over the entire heating period of nine hours by introducing additional quantities of benzene as necessary (with oil bath temperature of 100-110° C.). On allowing the reaction mixture to cool to about 60° C., 400 ml. of methanol was added and the pale yellow product was collected on a filter, washed with methanol and dried under reduced pressure by employing rubber sheet over the funnel. Yield: 224 g. (91% of theory); M.P. 176-178° C. (d).

Analysis.—Found: C, 47.69; H, 7.37; N, 6.83, 6.86.

Depending on the concentration of the benzene in the reaction mixture, the reaction temperature and thus the time for the completion of the reaction may vary. However, when the reaction was shortened to four hours, somewhat inferior yield (70-80%) and quality of product was obtained. Prolonged heating at higher temperatures resulted in decomposition with darkening of the reaction mixture and a lower yield and an inferior product. In some instances it was noted that an inert atmosphere as nitrogen for the reaction mixture could be used advantageously.

Other glycol solvents, for example ethylene glycol or a mixture of propylene glycol and ethylene glycol, may be used as reaction solvent. In some cases, it may be desirous to omit the use of the benzene-water azeotrope for the removal of water, and instead, employ reduced pressure.

EXAMPLE 3

A mixture of 19.4 g. (0.1 mole) of piperazine hexahydrate, 36 g. (0.2 mole) of glucose and 75 ml. of water was warmed on a steam bath until solution resulted. Then the mixture was allowed to stand at room temperature for two weeks. The resulting colorless product was collected on a filter and washed with 200 ml. of warm methanol. Yield: 16 g. (39%); M.P. 186-188° C. (d).

Analysis.—Found: N, 7.05, 7.13.

On cooling the above filtrate at 0° C. for about one week, 3 g. of the lower melting form was obtained, M.P. 172-174° C. (d). Total yield: 19 g. (46%).

When a solution of 1.94 g. (0.01 mole) of piperazine hexahydrate, 3.60 g. (0.02 mole) of glucose and enough water to give a total volume of 19 ml. was allowed to stand for eighteen days, no solid was obtained. However, on diluting this solution with 80 ml. of methanol a precipitate began to form at once. After standing for one hour and filtering, an eighteen percent yield was obtained; M.P. 174-175° C. (d).

However, an increased yield was obtained when a large

excess of glucose was employed: 10.8 g. (0.06 mole) of glucose was dissolved in 12 ml. of water by warming. Then 1.94 g. (0.01 mole) of piperazine hexahydrate was added and the solution was allowed to stand at room temperature. After three days a solid had separated. After twelve days the mixture was diluted with 5 ml. of methanol, and filtered. The residue was washed with methanol and dried. Yield: 3.3 g. (80%, based on the piperazine) of colorless solid, M.P. 184-186° C. (d).

EXAMPLE 4

On stirring together a mixture of 1.94 g. (0.01 mole) of piperazine hexahydrate and 3.60 g. (0.02 mole) of glucose, a syrup was obtained. This was placed in a closed bottle for three weeks. The resulting semi-solid was triturated with methanol. The precipitate was collected on a funnel, washed with methanol and dried. Yield: 2.7 g. (66%) of pale yellow solid of M.P. 169-172° C. (d). Higher yields (80-90%) were obtained when larger quantities of glucose were employed in this reaction.

Although this product of the present invention undergoes slow change (partial hydrolysis and mutarotation) in water and dilute alkali, it is unaffected on exposure to the atmosphere or in suspension with anhydrous vehicles such as Carbowax 400 (polyethylene glycols), propylene glycol, Tween 80 (polyoxyethylene (20) sorbitan monoleate) or a mixture of two or more of these materials. Accordingly the product is preferably packaged for storage and use either in the anhydrous state or formulated in compositions using the above or similar nonaqueous carrier materials.

As a further characterization of the compound of this invention, it was acetylated by standard procedures with acetic anhydride to produce octa-acetyl-1,4-bis(D-glucosyl)piperazine; M.P. 236-237° C. (d).

While several particular embodiments of this invention are shown above, it will be understood of course that the invention is not to be limited thereto since modifications may be made and it is contemplated therefore by the appended claims to cover any such modifications as fall within the true spirit and scope of this invention.

I claim:

1. 1,4-bis(D-glucosyl)piperazine.
2. A process of preparing 1,4-bis(D-glucosyl)piperazine which comprises contacting glucose and piperazine for a period of time until a solid product is formed and separating said product from the reaction mixture.
